US0D1050731S

(12) United States Design Patent (10) Patent No.: US D1,050,731 S
(45) Date of Patent: * Nov. 12, 2024

(54) RING BOX

(71) Applicant: Shantou shangpin Technology Industrial Co. LTD, Shantou (CN)

(72) Inventor: Tao Chen, Shantou (CN)

(73) Assignee: Shantou shangpin Technology Industrial Co. LTD, Shantou (CN)

() Term: 15 Years

(21) Appl. No.: 29/869,414

(22) Filed: Dec. 30, 2022

(51) LOC (14) Cl. 03-01

(52) U.S. Cl.

USPC D3/294; D3/903

(57) CLAIM

The ornamental design for a ring box, as shown and described.

DESCRIPTION

FIG. 1 is a front perspective view of a ring box, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a front perspective view of the ring box, shown in an alternate configuration in a state of use.

The broken lines in the drawings illustrate the portions of the ring box that form no part of the claimed design.

1 Claim, 8 Drawing Sheets
